CLIP FOR A DISPLAY STAND FOR SUNGLASSES OR THE LIKE

Roy C. Brown, Canterbury, Conn., assignor to Artistic Wire Products Company, Inc., Taftville, Conn., a corporation of Connecticut

Filed June 9, 1966, Ser. No. 2,628

Term of patent 14 years

(Cl. D80—10)

FIG. 1

FIG. 2

FIG. 3

FIG. 5

FIG. 1 is a perspective view of a clip for a display stand for sunglasses or the like, incorporating my novel design.

FIG. 2 is a top plan view thereof.

FIG. 3 is a side elevational view thereof.

FIG. 4 is a front elevational view of my novel clip.

FIG. 5 is a side elevational view of an alternate form of my novel clip.

FIG. 6 is a top plan view of the alternate form shown in FIG. 5.

I claim:

The ornamental design for a clip for a display stand for sunglasses or the like, as shown.
